STOVE SUPPORT

Clement Ehret, White Plains, N. Y.

Application December 24, 1938, Serial No. 247,571

4 Claims. (Cl. 254—100)

This invention relates to stoves and more particularly domestic kitchen stoves of the general character forming the subject matter of my application, Serial No. 203,760, filed April 23, 1938, maturing into Patent No. 2,141,742, on December 27, 1938, of which this application is a continuation in part.

This type of stove is characterized generally by the provision of a stationary base on which a stove body, comprising one or more ovens and a cooking top portion, is mounted for vertical adjustment and rotation with respect to such stationary base.

The present stove provides novel and efficient means for raising and lowering the stove body with respect to the base and also means whereby the stove body may be rotated and locked in any desired position of vertical and rotary adjustment.

Features of the invention, other than those adverted to, will be apparent from the herein-after detailed description and claims, when read in conjunction with the accompanying drawings.

The accompanying drawings illustrate different practical embodiments of the invention, but the constructions therein shown are to be understood as illustrative, only, and not as defining the limits of the invention.

Figure 1 is an elevation of a stove embodying the present invention, with portions of such construction shown in vertical section.

Figure 2 is a horizontal section taken in the plane of the line 2—2 of Figure 1.

Figure 3 is a fragmental section taken in the plane of the line 3—3 of Figure 2 with certain parts shown in elevation.

Figure 4 is a fragmental perspective of a worm operating splined shaft shown in the preceding views.

Figure 5 is an end view of one of the worms, internally splined to cooperate with the shaft of Figure 4.

Figure 6 is a view similar to Figure 1, but showing amplifications in operating means.

Figure 7 is an end view of the structure shown in Figure 6.

The stove of the present invention comprises a stationary base 1 and a stove body 2, the latter of which is rotatable and vertically adjustable with respect to the base 1. The base comprises an upstanding cylindrical portion 3 into which is telescopically received a stem 4 which, in the construction of Figures 1—5, is rigidly and permanently secured to the stove body. Referring to these figures in particular, the stem 4 is cylind-

rical in form and is provided with vertically spaced apart annular grooves or channels 5, the spacing being substantially the same as the width of the channels. The upper end of the cylindrical portion of the base is flanged outwardly, as indicated at 6, to form an annular chamber or seat in which is received a ring gear 7 which bears upon the base of such annular chamber and embraces the stem 4.

The ring gear 7 has worm teeth in its outer periphery and carries, on its inner periphery, one or more projecting keys 8, rigid with the ring gear, and these keys are adapted to work in shallow vertical keyways 9 cut into the stem 4 so that the stem can slide up and down through the ring gear but is locked against rotation thereto. Thus rotation of the ring gear will impart rotation to the stem 4 and consequent rotation to the stove body 2.

Preferably cast integral with the base 1 is a housing 10, the conformation of which is clearly apparent from Figures 1 and 2. In this housing are located the various operating parts by means of which the stem may be selectively raised, lowered and rotated. To provide for the vertical adjustment of the stem, a shaft 11 is journaled for rotation in the housing 10 and has affixed thereto a pinion 12 adapted to mesh into the grooves 5 of the stem 4, which, because of the formation of these grooves, constitutes, in effect, a cylindrical rack. Through rotation of the pinion 12, the stem may be raised and lowered and the cylindrical character of the rack permits of rotation of the same with reference to the pinion 12.

Also journaled for rotation in the housing 10 is a worm shaft 13, capable of longitudinal reciprocation and on this worm shaft are mounted two worms, indicated by the reference numerals 14 and 15. The worm 14 is constantly in mesh with a subjacent worm wheel 16, fixed on the shaft 11 which carries the pinion 12. The worm 15 is in constant mesh with the ring gear 7. The worms are in axial alignment and are confined against longitudinal movement between the bearings in the housing and they are adapted to be independently rotated by the shaft 13. To permit of this such shaft is provided with one or more splines 17 (see Figure 4) and the worms are provided in their adjacent ends with splined sockets 18 and 19, shown best in Figures 2 and 5 identical with one another.

The outboard end of the shaft 13, in the construction of Figures 1—5, carries a hand wheel or crank 20 and through manipulation of this hand

wheel or crank, the shaft 13 may be longitudinally shifted to engage its spline 17 with either the socket 18 of the worm 14 or the socket 19 of the worm 15. When engaged with the socket 18, 5 as shown in dotted lines in Figures 1 and 2, rotation of the wheel 20 will cause power to be transmitted from the shaft 13, through worm 14 and worm wheel 16 to the shaft 11 which, in turn, will transmit power through the pinion 12 to the 10 cylindrical rack and the stove body will be raised or lowered, depending upon the direction of rotation of the hand wheel. By virtue of the worm and worm wheel connection in this train, the stove will be automatically locked in any position 15 of vertical adjustment when the hand wheel is released and will remain in such position until the hand wheel is manipulated to effect a positive adjustment in the manner stated.

It is be assumed that the hand wheel has been 20 manipulated to bring about the desired vertical adjustment of the stove body, said body may be rotated at the will of the operator by shifting the hand wheel from the dotted line position of Figure 2 to the full line position, in order to shift 25 the shaft 13 to move spline 17 into the socket 19 of the worm 15. When the parts are thus positioned rotation of the hand wheel will impart rotation to the ring gear which, being keyed to the stem 4, will rotate the stove body in either 30 direction depending upon the rotation of the hand wheel. When the hand wheel is thereafter released the worm wheel and ring gear will lock the stove body against inadvertent rotation.

It will thus be apparent that the stove body 35 may be vertically adjusted or rotated at the will of the operator and, at the conclusion of either operation, will be locked in position, so that it cannot inadvertently get out of adjustment.

The stove body will, in practice, be provided 40 with appropriate ovens and a cooking top, with each of which are provided suitable burners or other heating elements to which a suitable heating medium will be fed in a manner to be uninterrupted by either vertical adjustment or rotation 45 of the stove body. The means for feeding this heating medium will vary depending upon the character of such medium. For oil, gas or other fluid heating, medium tubular connections are employed, whereas for electricity, wiring connections 50 are substituted.

For illustrative purposes I have shown provisions for the feed of gas, comprising a gas feed pipe 21 connected to telescoping pipe sections 22 and 23. Section 22 is rigid with the base while 55 the section 23 is rigid with the stove body and extends to the heating elements. Suitable packing glands may be provided between these sections, but in any event they allow for the raising and lowering of the stove body, as well as its 60 rotation, without interruption of the feed of heating medium.

The structure of Figures 6 and 7 embodies all of the parts thus far described in connection with Figures 1-5, except the hand wheel and, in 65 lieu of the hand wheel, there is substituted treadle arrangements for shifting the worm shaft 13 longitudinally and for rotating said shaft in either direction. To provide for longitudinal shifting of the shaft, there is firmly affixed there- 70 to a flanged collar 24 and between the flanges of this collar are positioned rollers 25 carried by the bifurcated upper end of a lever 26. This lever is pivoted at 75 to a bracket 28 on the base and carries at its lower end oppositely offset foot 75 pedals 29 and 30. When the pedal 29 is pressed

downwardly by the foot, the worm shaft is shifted to the right to engage the spline 17 with the worm 14 and when the pedal 30 is depressed by the foot, the shaft 13 is shifted to the left to engage the spline with the worm 15. 5

The shaft 13 extends beyond the flanged collar and carries thereon a ratchet wheel 31 and a pawl carrier 32. The ratchet wheel 31 is keyed to the shaft 13, so that when the ratchet is rotated, the shaft is rotated, but the pawl carrier 32 is freely rotatable on the shaft. The pawl carrier 32 has an upstanding arm 33 to which is pivoted a double acting pawl 34, rigid with its pivot spindle 35. This spindle 35 projects through an arcuate slot in the housing 10 and 15 carries a handle 36 by means of which it may be manually tripped over from the left hand position shown in Figure 7 to the right hand position in order that it may be conditioned to operate the ratchet wheel 31 in either direction. 20 The ratchet carrier has affixed thereto, exteriorly of the housing, a lever 37 and secured to this lever is also a pedal link 39 having a foot pedal 40. The lever 37 preferably has an upturned end portion projecting into readily accessible 25 position and provided with a handle 38 whereby it may be grasped and directly operated. The link 39 is guided at its lower end by a guide rod 41 slidably projecting into a guide 42 on the base. By this means the lever 37 may be oscillated in a vertical plane, either by a hand directly gripping the handle 38 or by foot operation of the pedal 40. Downward pressure of the foot will depress the lever while a spring 43 will elevate it. Through manipulation of the lever 35 either by the hand or foot as described, the pawl will cooperate with the ratchet to rotate the worm shaft 13, by a step by step movement, for the purpose of either raising or lowering the stove or to rotate the same, depending upon the 40 position of the spline 17 with respect to the worms 14 and 15. The direction of rotation of the shaft 13 will of course be controlled by the position of the pawl 34, which may be manually moved from one side to the other to control the 45 direction in which it positively operates upon the ratchet wheel 31.

It will thus be apparent that in the construction of Figures 6 and 7 a single treadle may be used to serve the dual purpose of vertically adjusting and rotating the stove body, while additional foot operated means selectively controls the delivery of power to bring about either vertical adjustment or rotation. If desired, however, I may provide independent means for rotating and vertically adjusting the stove body and this means may be hand operated or treadle operated. For example, I may drive one of the worms 14 by a crank, lever, or treadle, to obtain vertical adjustment and use an entirely separate 50 crank lever or treadle to operate the worm 15 to rotate the stove. In such case, the worms 14, 15 might well be fixed on their own individual shafts with the operating means connected to each shaft. Likewise the vertical adjustment 55 means of Figures 6 and 7 may be incorporated in a structure without including the means for rotating the stove body and, conversely, the means for rotating the stove body may be incorporated in a construction without providing the means 60 for vertically adjusting the same.

In the forms of the invention which I have thus far described, the ring gear is keyed to the stem 4, so that there is a positive drive from the ring gear to the stove body. I may, however, 75

eliminate the sliding key connection between these parts and line the inner periphery of the ring gear with friction shoes or some suitable friction material, such as leather, fiber or the like, so that the ring gear will have sufficient friction with the stem to drive the latter through such friction connection. The advantage of this arrangement is that if it is desired to quickly rotate the stove body, it may be grasped and turned against the friction between its stem and the ring gear.

For the purpose of illustration I have shown in the drawings a gas stove, but I wish it understood that this invention is not limited to gas stoves as it may be used for oil stoves, vapor stoves or electric stoves. Similarly, the shape of the base, stove body and other parts may be varied within wide limits according to the taste of individual designers without departing from this invention.

The foregoing detailed description sets forth the invention in its preferred practical forms, but the invention is to be understood as commensurate with the appended claims.

Having thus fully described the invention, what I claim as new and desire to secure by Letters Patent is:

1. A stove body support comprising a base, a body supporting stem telescoping with respect to the base and having a coaxial cylindrical rack, a ring gear supported on the base and embracing said cylindrical rack for rotation therewith, a pinion supported by the base and meshing with said rack, a worm wheel rigid with said pinion, a pair of worms arranged in coaxial relation and meshing respectively with the worm wheel and ring gear and each worm having a clutch member, a common operating shaft extending through

both worms and provided with a clutch member adapted, through longitudinal movement of the shaft, to engage with the clutch member of either worm selectively, and means for rotating said shaft.

2. A stove body support comprising a base, a body supporting stem rotatably supported on the base, a ring gear keyed to the stem for rotation therewith and for sliding movement with respect thereto, means for rotating the ring gear to rotate the stem, and means for vertically moving the stem while the ring gear remains stationary.

3. A stove body support comprising a base, a body supporting member mounted on the base for vertical adjustment and for rotation with respect thereto, a vertical rack carried by said member and rigid therewith, an annular gear embracing said member for relative axial movement and for rotation therewith, a pinion supported on the base and meshing with the rack to raise and lower the member, and a pinion mounted on the base and meshing with the annular gear to rotate said member.

4. A stove body support comprising a base, a stove supporting stem telescoping with respect to the base, a vertical rack on said stem, an annular gear secured against rotation to the stem with respect to which the stem is axially movable, a single operating shaft supported on the base for rotation, and means for selectively connecting said shaft to the annular gear and to the rack whereby operation of said shaft may rotate the supporting stem or vertically adjust the same as may be desired.

CLEMENT EHRET. 35
